Letters Patent No. 308. Dated August 13, 1850

Dec. 308

The Schedule referred to in these Letters Patent and making part of the same.

To all whom it may concern:

Be it known that we, Sherman S. Jewett and F. N. Root of Buffalo in the County of Erie and State of New York have invented or produced a new and ornamental design for Stoves, of which the following is a full, clear and exact description, reference being had to the accompanying drawings, which form part of this specification, and in which figure 1 is an elevation of the front plate of the stove, figure 2 is a plan of the top plate, figure 3 is a plan of the bottom plate, and figure 4 an elevation of an end plate.

The design represented on the front plate (figure 1) is reproduced on the back plate of the stove, a sufficient portion of the ornamental parts being removed and the plate being altered to adapt it to the discharge of the smoke by means of a pipe which is fitted to it. The design consists principally of three distinct portions, the outer A, A', forming borders near the sides of the plate and the remaining one occupying the space included within the first two. The two portions A and A' are alike, and are each composed of a series of pendant leaves a divided into three distinct sets by bands b, the lower extremity of the lowest set terminating in a pendant c. The central portion of the plate is occupied by a series of leaves D, voluted and entwined with each other as represented in the drawing.

The top plate of the stove (figure 2) is perforated at its middle with a circular hole surrounded by a moulding C, and the space contained between this moulding and the margin of the plate is ornamented with four symmetrical devices, D, each composed of leaves d whose stems e are voluted as shown in the drawing.

Des. 308

387

The bottom plate (figure 3) projects at the front, E, to form a hearth. Its edges are ornamented with a raised margin, composed of leaf formed figures f, f, whose outer indented edges give form to the edges of the plate. There is also a raised margin F immediately surrounding that portion of the plate on which the side plates are erected. This margin is covered by leaf-formed ornaments springing in each direction from the corners and meeting each other midway between the corners.

The end plates are ornamented with devices to match those of the back and front plates and like those consist principally of three portions, the two outer & forming borders, and the inner ornamenting the space between the outer two. The outer two are each composed of pendant leaves g, g, divided by bands h, and terminating at their lower extremities in pendants i. The central device is composed of leaves (k) variously convoluted and entwined as shown in the drawing. One or both these end plates are fitted with doors, the line of opening being shown in figure 4.

What we claim as our invention and desire to secure by Letters Patent is the shape and configuration of the ornamental plates for stoves herein described.

In testimony whereof we have hereunto subscribed our names.

Witnesses.
